*Seth Graham**Patent No. X7059.*

The Schedule referred to in these Letters Patent and making part of the same containing a description in the words of the said Seth Graham himself of his improvement in the machine for forming flat bodies.

This machine is stationary in the use of a carding machine and is entirely connected with it both in its construction and operation.

The wool is discharged from a cylinder of the carding machine called the doffer, in a thin web which passes under the tongue of a wire which extends from one side of the carding machine to the other in a curved form.

The web is formed into flat bodies by the operation of two conical blocks that lay in a horizontal position and in their operation receive these different motions. These conical blocks which are sixteen inches in length are so placed that the two larger bases come in close contact with each other. The diameter of the large base being fourteen and half inches, and the diameter of the smaller base seven inches and one fourth. The small ends being globulated. The blocks are placed on two pairs of cone rollers which are twenty one and a half inches in length, seven inches diameter at the larger end three inches and a half at the smaller end. The small ends of these also are globulated. The cone rollers, and also the blocks, are made hollow; and thro' the center of the rollers are small iron shafts the ends of which project out sufficient long to project beyond the rollers so as to receive inward toward the carding machine, and in their operation they give motion to the blocks. The blocks and rollers together with their appendages, have two rebating motions. The first is from right to left alternately and is effected by a piece of timber sometimes called the vibrating floor. This floor is a piece of plank of pine or other suitable kind of wood about forty inches in length and twenty two inches in width, and is known as mainly that of an open fire cut off at the place where

the stocks unite with the spread substituting for the part suspended a stem that is sixty four inches in length and three by two inches square at the extremest end of which and about two inches from the end is a perforation half an inch diameter which rests on a pivot that is confined to the floor of the machine building.

The vibrating floor works on a curved railway of sufficient length to accommodate the extent of the motion or vibration. The railway is composed of a curved piece of board about three inches in width and one inch thick confined to the floor of the machine building by any proper fixings with the concave edge towards the vibrating machine. A piece of iron plate one inch in width and three sixteenths of an inch thick is firmly fixed to the concave edge of the curved piece of board. The length of the plate corresponding to the length of the board and the edge of the plate projecting above the surface of the board half an inch. on this projection two friction Rollers, barrel, which work in suitable mortices made in the vibrating floor. These friction Rollers are three and half inches diameter and half an inch thick with grooves adapted to work on the projection of the railway. the distance from the friction Rollers to the outward edge of the floor is five inches and a half and the space between the rollers is twenty six inches and three fourths. The second vibration motion is effected by another piece of the machine. which is a piece of board in the form of a diamond, four feet in length from one point to the other (the points being rounded a little) and eighteen inches in width called the upper vibrating floor. and the space occupied between the floors is about ten inches. The upper floor is supported by a piece of iron plate in the form of an arch which stands upon the lower floor directly over the centre line and two inches from the front side. This arch is confined in its place by screw fastenings. A perforation half inch diameter is made through the upper floor. on the centre line at a distance of two inches and a half, from the front side and an iron bolt passes thro' this and a corresponding perforation made in the top of the iron plate on which the floor stands.

The floor moves upon this belt as upon a pivot. To prevent the rotation of this floor, a curve railway is fixed on the under surface of the floor with the concave side towards the point on which the floor turns. This railway may be of cast iron or other hard metal, eighteen inches in length, one inch and a half in width, and half an inch thick with a projection rising on the convex side one fourth of an inch. This railway is fitted to operate in grooves made in the circumference of the floor. Rollers, that are two inches and a half in diameter and half an inch thick, These friction rollers work in mortises made in the lower floor, on a sweep of eleven inches, and three eighths from the centre of the motion to the centre of the grooves in the railway. All the friction rollers may be made of cast iron or other hard metal. The mortises in which the large friction rollers work are covered with wooden caps, which are about four inches long, two inches wide and one inch thick. To prevent the upper railway from being interlocked with motion by the cap pieces, small grooves are made in the upper surface, corresponding to the size and motion of the railway. The distance from the centre line on the lower floor to the centre of the grooves in the last mentioned friction rollers respectively is four inches, and three fourths.

An arch is erected on the upper floor, the feet of which stand on a conic line drawn lengthwise of the floor. This arch is a curve piece of iron that is one inch and a half in width and half an inch thick. The distance from the floor to the top of the arch is seven inches, and the space occupied between the feet of the arch is about twelve inches. The feet which stand outward two inches, are confined to the floor by screws which pass thro' perforations made in them.

The bearings which sustain the large ends of the cone rollers consists of two pieces of iron each of which is two inches in length, one inch in width and half an inch in thickness. In one end of these pieces is an oblong aperture, two inches in length and half an inch in width. These ends are placed one upon another so that they will lap each other three inches, and being thus secured, they are placed

transversely across the top of the above described work and confined in that position by a screw bolt that is half an inch square and passes through a corresponding perforation made in the top of the work previous by at the centre with a nut on the upper end of the screw bolt.

The small end ends are elevated in a curve from about four inches and semi-circular sockets formed in them is adapted to receive and sustain the guides on the large end of the cone roller.

The bearings which support the small ends of the cone roller are two plates of iron that are one inch in width and half an inch in thickness. These plates of iron are turned in the form of a right angled triangle the perpendicular part being twelve inches in height and the hypotenuse which runs as the surface of a brace is fifteen inches in length. Three inches of the lower end of the perpendicular (exclusive of the height) and also the brace turned up which turns serve as feet to rest on the floor when they are confined by screws that pass thru the feet into the floor at the centre line.

The space between the upper ends of the perpendicular parts corresponds to the entire length of the cone roller. On the upper ends of the perpendicular part of the triangular pieces at about two inches from the top are perforations half inch diameter in which are iron screw bolts with nuts on the raised ends. These bolts and nuts are fitted to receive and confine two pieces of iron plate which are six inches long, one inch wide and five eighths of an inch thick with apertures or mortises made thru them, four inches in length and half an inch in width. These pieces are attached to the perpendicular parts of the triangular pieces and confined in their places by the iron bolts at the top. By sliding these pieces upward or downward their height is adapted to the proper position of the cone roller. On the top of these sliding pieces is a piece of iron plate four inches long with semi-circular sockets in the ends fitted to receive and sustain the guides on the small ends of the cone roller. On the large end of the box cone roller which lay toward the carding machine, on the small which, stand down on either hand mortise whose diameter are six

inch and a half, and a row of cog's constructed on the bevelled surface of each wheel, interlock with other, on the large end of the left hand cone roller which lies in front is a circular piece of iron about $\frac{1}{2}$ plate, the diameter of which is seven inches, giving a projection of one fourth of an inch from the surface of the roller, and this projected part of the plate works in the seam between the large ends of the blocks.

A small bevelled wheel three inches and one fourth diameter, the cog's of which interlock with the cog's on the right hand of the two above described wheels, works horizontally on a small iron shaft that is three inches in length and stands in a vertical position directly under the guides on the cone rollers. The guides on the upper end of this shaft works in a perforation made in, and near the end of a piece of iron plate that is nine inches in length, one inch in width and one fourth of an inch thick, the inward end of which passes under the arch piece with a perforation made in it fitted to receive the iron bolt at the top of the arch, by which bolt this end is confined. In the middle of is confined to the iron which lays above by proportionately small pins, these both pieces, the guides on the lower end of this shaft works in a similar piece of iron secured by similar fastening, at the same ends. Under the bevel wheel and on the same shaft is a wood or beech wheel three inches diameter and one and a half thick, on the opposite side of, and nearly equal distance from the arch is another small iron shaft one inch in length in a vertical position near the upper end of which is a pulley three and a half inches diameter and one inch and a half thick. This pulley is connected with the one on the other shaft by a suitable band. Near the lower end of this shaft is another wooden pulley three inches diameter and two and a half thick. The guides on the lower end of this shaft works in a socket that is confined to the upper vibrating iron and the guides on the other end works in a perforation made in a piece of iron plate that is two inches long, one inch and one fourth in width and one fourth of an inch thick, the other end being confined by the bolt that passes through arch piece at the top. The

cone roller receives motion from the doffer through medium of a series of pulleys, bands, and wheels, as follows, viz. A pulley ten inches diameter is fitted on the left end of the doffer inside of the pulley that belongs to the doffer, and this pulley is connected with another nearly under it, the shaft of which extends across the whole width of the carding machine, the pulleys of this shaft being supported by suitable bearings that are confined on the upper surface of the side rail. On the bottom of this shaft, and inside of the opposite side rail is another pulley or cylinder of a length suited to present three plain surfaces of different diameters which are of sufficient width to receive a suitable band. The smallest diameter is six inches and lays toward the opposite side of the machine—the longer diameter is seven inches, and the largest is eight inches. This cylinder is connected by a band with another of like construction, the shaft of which extends across the width of the carding machine at a small distance from the outward end of the stem of the lower frame and the pulleys of this shaft are confined to the inside of the side rail. The smallest diameter of the last mentioned cylinder placed in a position opposite to that with which it is connected. The several surfaces of different diameters, presented on the periphery of these two cylinders, are designed to vary the speed of the cones rollers by moving the band that connects them from larger to smaller and vice versa. On the middle of the shaft on which the last mentioned pulley works is a spur wheel six inches diameter which interlocks with another of like form and dimension and the mesh of these two wheels must coincide over the pivot on which the vibrating stem operates. A pulley ten inches thick and six inches diameter is placed on the shaft of the last mentioned spur wheel and comes in close contact with the left side of it. The shaft of this wheel and pulley is four inches in length and the guard now works in perforations made in suitable pieces of iron plate that are confined to the sides of the vibrating stem. The last mentioned pulley is connected by a band with the pulley on the lower end of the central shaft situated on the front of the upper vibrating stem.

and the pulley on the upper end of this shaft being connected with the pulley on the opposite side of the arch as before described completes the series of parts which communicate motion from the doffer to the carding machine. The lower vibrating floor receives motion from a cylinder of the carding machine called the feeder through the medium of a series of pulleys, the first of which is a pulley four inches diameter that works on the shaft of the feeder frame. This pulley is connected by a band with another which works directly under it, and is eight inches diameter. The shaft of this pulley is supported by iron bearings, one of which is confined to the side of the carding machine, and the other is confined to the floor of the machine building. On the same shaft and inside of the pulley last described is another pulley which is three inches diameter and is connected by a band with another twelve inches diameter that works in a horizontal position out side of the carding machine about twenty four inches forward of the rear post, grooves being made in the circumference of these two pulleys, fitted to receive the band that operates on them. The horizontal wheel is connected with the vibrating stem by an iron rod or axle with perforations made in it near each end. The perforation in one end works on a pivot inserted in the vibrating stem at the post directly opposite to the centre of the horizontal wheel and the perforation on the other end of the arm works on a movable pivot which is placed on the upper surface of the horizontal wheel at about six inches from the circumference. The movable quality of the pivot on the axle is designed to vary the extent of vibration, so as to correspond with the size of the blocks that are used whether they be large or small. By the operation of the horizontal wheel upon the vibrating stem the lower floor and its dependents are moved alternately from right to left. The second vibratory motion of the upper floor is effected by means of two rods, which pass around a pulley three inches diameter that works horizontally on the vibrating stem at a distance of six inches from the floor. One end of each rod is attached to the ends of the upper floor and passing round the pulley to the opposite side of the carding machine as there are four rods supporting the upper floor.

obliquely to the right or left, the end on the opposite side prevents it from making a circuitous motion like the other floor and consequently the cones roll, and blocks are kept in a position parallel to the cylinder from which the web of wool is discharged.

The specific sizes of the parts of this machine as they are stated in this specification are such as are found to be convenient but they may be varied without impairing the general construction of the machine. To work the machine above described the attendance of two workmen is necessary, one to feed the carding machines, and the other to tend the cone blocks. The workman receives the web as it is discharged from the doffer and applies the end to the blocks which form it into two flat bodies, that are separated by cutting with a pair of shears. Between the large ends of the blocks and where the web is winding round one block the heat body is removed from the other and the block returned to its place in season to receive the web in its return —

The machine above described, to claim
